UNITED STATES PATENT OFFICE.

HAROLD L. HAYNES, OF CLEVELAND, OHIO, ASSIGNOR OF ONE-HALF TO HENRY J. WALSER, OF CLEVELAND, OHIO.

ESCAPEMENT MECHANISM.

Application filed December 19, 1919. Serial No. 345,889.

To all whom it may concern:

Be it known that I, HAROLD L. HAYNES, a citizen of the United States, residing at Cleveland, in the county of Cuyahoga and 5 State of Ohio, have invented certain new and useful Improvements in Escapement Mechanism, of which the following is a specification.

This invention relates to time pieces and 10 particularly to escapement mechanism therefor. The invention has particular relation to clock movements or time pieces designed for running over an extended period, such as eight days, a month or a year, such as clock 15 movements used in connection with time recording or signal systems, or for any other purpose.

Clock movements designed for long 20 periods of operation require large powerful springs, which necessitate the use of a pendulum or other heavy escapement mechanism. The present invention has for its object to provide improved escapement mechanism for use with long period clock movements, 25 and the delicacy and accuracy of which may be the same as a watch escapement but which is not affected by the heavy clock spring. A further object of the invention is to provide improved escapement mechanism 30 in which the escapement is directly affected by a secondary relatively light spring of lower power, to thereby protect the escapement, but which secondary spring is rewound at relatively frequent intervals 35 so as to maintain its power factor substantially uniform.

A further object of the invention is to provide governing means for controlling the transfer of power from a primary spring 40 having a relatively large power factor to a secondary or intermediate spring of small power factor by the use of braking mechanism effective upon a relatively stationary part of the casing or frame, to thereby avoid 45 variation in time effect and compensate for lost motion or any wear of the parts.

A further object of the invention is to provide improved escapement mechanism of the general character indicated which can be 50 built or assembled in compact unit form so designed as to be capable of insertion in many forms of clock movements already assembled, thereby adapting it for clock movements already in use, and which arrangement also enables the escapement mech-

anism to be handled as a unit for repair, inspection and other purposes without effect upon the main clock movement.

Further objects of the invention are in part obvious and in part will appear more 60 in detail hereinafter.

The invention comprises the construction and arrangement of parts hereinafter described and claimed.

In the drawings, which represent one suitable embodiment of the invention, Fig. 1 is a front elevation; Fig. 2 is a sectional elevation on substantially the line 2—2, Fig. 1; Fig. 3 is a detail sectional elevation, on a larger scale, on the line 3—3, Fig. 2; and Fig. 4 is a detail sectional elevation on substantially the line 4—4, Fig. 3, connection between the brake levers and scroll being shown out of true position for purposes of illustration. 75

The invention is capable of application to any suitable or desired form of clock movement. For purposes of illustration the drawings show a simple clock movement which consists of the frame plates 1 connected by the usual pillars 2 and which plates are provided with or form the necessary bearings or supports for the rotating shafts or arbors. In the frame is mounted the main spring 3 provided with a winding shaft 4 and a gear 5 in driving relation with a pinion 6 on arbor 7. Said arbor is provided with a gear 8 driving a pinion 9 on a shaft 10 which in turn is provided with a gear 11 meshing with a pinion 12 on shaft 13. Shaft 13 carries a large gear 14. The train so far described is a usual clock train, with one of the arbors serving as the means for operating the clock hands. For example, arbor 10 may be the hand operating 85 shaft, which consequently turns in the clockwise direction Fig. 1. Gear 14 is the one usually connected to a pendulum or other corresponding escapement mechanism and in the present instance is the gear which supplies the power and which drives the escapement mechanism forming the subject 90 matter of this invention.

In a suitable portion of the main frame is located a plate 15 which may be secured to a main frame plate by the posts or pillars 16. This plate serves as the support for all of the members or elements of the escapement mechanism, so that by disconnecting the pillars 16 the escapement mechanism may be 105 110

removed as a unit without disturbing the assembly of the parts carried by plate 15 for the purpose of inspection or repair or said escapement mechanism can be shipped 5 or packed as a unit and by providing the necessary openings in the frame plates may be readily attached to a clock movement already in use as the substitute for the escapement mechanism therein contained.

10 Plate 15 is provided with short pillars 17 which serve to support two escapement frame plates 18, 19, of peculiar shape, as shown in dotted lines Fig. 1. Plate 15 also carries a cupped bearing member 20 which co-operates 15 with a portion of the plate 18 as the bearings for an arbor 21 carrying a pinion 22 in driving relation with the gear 14. Secured to rotate with said arbor is a sleeve or enlargement 23 carrying a disk 24 lying 20 within a hollow shallow circular recess 25 of plate 15, the periphery of said recess being provided with suitable braking material, such as a steel ring 26, which constitutes an internal brake drum. Upon the 25 disk 24 are pivoted at 27 two brake levers 28, the pivots for said levers lying near the periphery of the disk where said levers are provided with braking portions 29 of curved form designed to properly co-operate 30 with the drum or braking portion 26 of the plate.

At its opposite end, adjacent the plate 18, arbor 21 is secured to the inner end of a coiled secondary or intermediate spring 30, 35 whose outer end is connected to a pin 31 on a hollow casing 32 attached to a gear 33. Said gear is rotatable loosely on the arbor 21 and carries a cam disk or scroll 34 provided with two curved cam slots 35 to receive pins 36 located on the inner ends of 40 the brake levers 28. Gear 33 is operatively connected to a suitable ordinary watch escapement, such as what is known as an 18 size watch escapement, including the escape 45 wheel 37 operated by gear 33, the escape lever 38 and the balance wheel 39. The parts of this escapement are supported by the plate 19 before referred to.

The operation is as follows: The parts 50 are so arranged that the tendency of the main spring is to turn arbor 21 in the clockwise direction, Fig. 3. In the normal position of the parts, or in other words, when the movement is running, the pins 36 lie 55 intermediate the ends of the cam slots in the scroll in which they are engaged. In this normal condition also, arbor 21 has been turned sufficiently to wind the secondary spring 30, so that power is stored in said 60 spring sufficient to actuate the escapement. The unwinding movement of main spring 3 continues until the levers 28 have been bodily advanced by rotation of the disk 24 until 65 said levers have been turned sufficiently by the more slowly turning scroll to exert a

braking effect upon the brake drum and stop further movement of disk 24. The main clock train, up to and including gear 14 and arbor 21 is then held stationary. While said train is stationary (and in fact at all other times) the secondary spring 30 operates the watch escapement and continues the regular advance or rotation of the scroll 34. Rotation of said scroll gradually turns the levers 28 until finally they are released from braking effect upon the drum and the disk 24 is permitted to be again advanced by the main spring.

The effect is to transfer very small increments of power at relatively frequent intervals, to wit, fractions of a second, from the main spring 3 to the secondary spring 30. The watch escapement is always driven solely by the secondary spring and is in no way subject to the direct power of the main spring. Consequently the entire movement has the delicacy and accuracy of a watch but may be provided with a long or relatively large main power spring sufficient to operate the movement over an extended period. Furthermore, the sensitiveness and accuracy of the movement are governed entirely by the watch escapement and variation in the power effect of the main spring as it unwinds does not affect the accuracy of the time effect. Again, the braking effect which controls the transfer of power from spring to spring is exerted upon a relatively stationary portion of the frame or support and the movement is not affected by lost motion as is the case where the braking effect is between two parts both of which have movement, and also wear of the braking or other surfaces is automatically taken up by automatic adjustment of the pins 36 along the slots of the cam scroll.

When the movement is running there is no appreciable oscillation of the levers 28 on their pivots but they float, as it were, in a position in which very slight lever movement produces braking effect or releases the levers from braking action. The real operation is quite analogous to the governing effect in steam engines where the governor arms float in the governing position.

Release of the braking levers to allow further winding of the secondary spring is not an effect consequent upon the power of the secondary spring, for the reason that when said levers are stationary and in braking relation with the drum the natural turning movement of the scroll is in the proper direction to allow the pins 36 to travel down-hill, as it were, toward the axis of the arbor 21. The tendency of the disk 24 to rotate clockwise, as a result of the pressure of main spring 3, always exerts an effect upon levers 28 tending to move them to release, so that essentially it is the power of the main spring which produces the releasing action and the

secondary spring merely controls said releasing by its effect upon the scroll.

The greater the power effect of the main spring the greater is the pressure of the pins 36 upon the sides of the cam slots, but at the same time, the greater is the tendency of said pins to travel down hill, as before stated, so that the effects are balanced at all tensions or pressures of the main spring.

10 Therefore the swing of the balance and beat effect are uniform at all times.

What I claim is:

1. Escapement mechanism, comprising a time piece movement provided with a support, said support carrying a secondary spring, an escapement operated by one end thereof, an arbor adapted for driving connection with the time piece train for winding said spring, and means rotatable with 15 said arbor and movable relative thereto and operated by said secondary spring for controlling the winding effect thereon.

2. Escapement mechanism, comprising a time piece movement provided with a support, said support carrying a secondary spring, an escapement operated by one end thereof, means adapted for driving connection with the time piece train for winding said spring, and means operated by said 25 secondary spring for controlling the winding effect thereon, said means including braking levers effective upon a stationary portion of said support, and a rotatable actuating disk therefor.

3. Escapement mechanism, comprising a time piece movement provided with a support, said support carrying an arbor driven by the time piece train, a secondary spring operated thereby, an escapement actuated by 30 said secondary spring, and braking mechanism controlled by said secondary spring and rotatable with said arbor and movable relative thereto to regulate the winding effect upon said secondary spring.

4. Escapement mechanism, comprising a time piece movement provided with a support, said support carrying an arbor driven by the time piece train, a secondary spring operated thereby, an escapement actuated by 45 said secondary spring, a stationary brake drum, brake levers effective thereon and rotating with said arbor, and means operated by said secondary spring for controlling the operation of said levers.

5. Escapement mechanism, comprising a time piece movement provided with a support, said support carrying an arbor driven by the clock train, a secondary spring op-

erated thereby, an escapement actuated by said secondary spring, a stationary brake 60 drum, brake levers effective thereon and rotating with said arbor, and a cam scroll actuated by said secondary spring and operatively connected to said levers for controlling the winding effect upon said secondary 65 spring.

6. Escapement mechanism, comprising a time piece movement provided with a support, said support carrying an arbor driven by the timepiece train and an annular braking surface surrounding said arbor, braking levers effective upon said surface and rotatable with and movable relative to said arbor, an actuating disk concentric with said arbor and rotatable relative thereto for actuating said levers, and a secondary spring 70 connecting said arbor and disk.

7. Escapement mechanism, comprising a time piece movement provided with a support, said support carrying an arbor driven by the timepiece train, a secondary spring 75 secured to and coiled around said arbor, a disk concentric with said arbor and actuated by said secondary spring, and movable braking levers actuated by said disk for controlling the winding effect upon said secondary 80 spring.

8. Escapement mechanism, comprising a time piece movement provided with a support, said support carrying an arbor driven by the timepiece train, a secondary spring secured to and coiled around said arbor, a disk concentric with said arbor and actuated by 85 said secondary spring, and movable braking levers actuated by said disk for controlling the winding effect upon said secondary spring, said braking levers being carried by a part rotatable with said arbor.

9. Escapement mechanism, comprising a time piece movement provided with a support, said support carrying an arbor driven by the timepiece train, a secondary spring secured to and coiled around said arbor, a disk concentric with said arbor and actuated by 90 said secondary spring, movable braking levers actuated by said disk for controlling the winding effect upon said secondary spring, said braking levers being carried by a part rotatable with said arbor, and a stationary annular braking surface concentric with said arbor and cooperating with said 95 braking levers.

In testimony whereof I affix my signature.

HAROLD L. HAYNES.
